UNITED STATES PATENT OFFICE.

EARL H. ODELL, OF CHICAGO, ILLINOIS.

VIOLET-RAY VACUUM CUP.

Application filed June 24, 1927. Serial No. 201,057.

This invention relates to a violet ray quartz vacuum cup and to a method of using the same in connection with violet ray treatments of the human body to subject a localized portion of the body to the action of ultra-violet rays, while at the same time putting that portion of the body under reduced pressure.

It is an object of this invention to provide 10 a quartz vacuum cup that may be applied to a localized portion of the body to draw the blood to the surface of such localized portion so that more effective treatment with ultra-violet rays can be obtained.

15 Other and further important objects of this invention will become apparent from the disclosures in the following description and appended claims.

In the accompanying drawings which 20 illustrate a preferred embodiment of this invention and in which similar reference numerals refer to similar features in the different views:

Figure 1 is a top plan view of a violet ray 25 quartz vacuum cup embodying the principles of my invention.

Figure 2 is a sectional view of the same taken on line II-II of Figure 1, with parts in elevation.

30 As shown on the drawings:

The reference numeral 1 indicates a dish-like vessel formed of material capable of transmitting ultra-violet rays. Fused quartz is known to be especially adapted for this 35 purpose. Said vessel 1 is provided with a rim 2, all points of which lie in substantially the same plane. Said rim 2 is formed with a wedge-shaped recess 3 into which is inserted a gasket 4 of some resilient material 40 such as rubber. An aperture 5 is formed in one end of the vessel 1 and a suction bulb 6 is connected thereto by means of a flexible tubing 7 for the purpose of exhausting the space inclosed by the vessel 1.

45 In using the device, the vessel 1 is applied to the particular portion of the patient's body to be treated, with the gasket 4 in tight contact with the surface of the body. The bulb 6 is then compressed and sufficient air 50 exhausted from the space inclosed between the vessel 1 and the body surface to cause the blood to be drawn to the surface so inclosed. Violet rays are then directed toward the vessel 1 and transmitted therethrough to the 55 body surface covered by said vessel 1. It

has been found that this method of treating the surface of the body with ultra-violet rays is much more effective than the ordinary method, due to the fact that the blood is drawn to the surface and is thereby subjected more directly to the effect of the rays. 60

It is obvious that the shape of the vessel 1 may be varied to conform with different parts of the body so that localized treatments may be applied wherever the greatest 65 benefit is to be derived. It is also apparent that the type of suction applying device is immaterial so long as the particular device employed is capable of partially exhausting the air from the space inclosed by the vacuum cup. An ordinary rubber bulb such as used in syringes serves the purpose satisfactorily. 70

I am aware that many changes may be made and numerous details of construction 75 may be varied through a wide range without departing from the principles of this invention and I, therefore, do not purpose limiting the patent granted hereon, otherwise than necessitated by the prior art. 80

I claim as my invention:

1. A device of the class described, for use in treating the body with ultra-violet rays, comprising a dished member formed of material capable of transmitting ultra-violet 85 rays and means connected with said member for creating sub-atmospheric pressure therein when said member is applied to the surface of the body.

2. A device of the class described, comprising a quartz dishlike vessel adapted to be applied to the surface of the body to transmit ultra-violet rays thereto and means for partially exhausting the space inclosed between said vessel and the body to draw the 90 blood to the surface inclosed by said vessel. 95

3. A device of the class described, comprising a dishlike vessel formed of quartz, a resilient gasket secured to the rim thereof for forming an air-tight joint when the vessel is positioned upon the surface of the body and a suction producing means connected to said vessel for partially exhausting the space inclosed between the vessel and the body surface. 100 105

In testimony whereof I have hereunto subscribed my name at Chicago, Cook county, Illinois.

EARL H. ODELL.
